UNITED STATES PATENT OFFICE.

ELISE GOLTSTEIN, OF COLOGNE, GERMANY.

BOTTLE CAP OR CLOSURE FOR BOTTLES, JARS, OR OTHER RECEPTACLES.

No. 874,670.

Specification of Letters Patent.

Patented Dec. 24, 1907.

Application filed September 10, 1907. Serial No. 392,089.

To all whom it may concern:

Be it known that I, ELISE GOLTSTEIN, subject of the Emperor of Germany, residing at Cologne, Rhine Province, Empire of Germany, have invented certain new and useful Improvements in Bottle Caps or Closures for Bottles, Jars, or other Receptacles, of which the following is a specification.

My invention relates to improvements in 10 bottle caps or closures for bottles, jars, or other receptacles, and more particularly to that class of caps or closures comprising a capsule of sheet metal which can easily be torn and adapted to be rigidly connected to 15 an outer or inner shoulder provided on the neck of the bottle or receptacle and thereby to clamp a cork or sealing disk to the neck or upper portion of the bottle or jar, and which capsule is formed, at its flat portion, with a 20 tongue-like thumb-piece which can be easily raised out of the flat portion of the capsule and grasped by the fingers of an operator, in order to tear the capsule and thereby to open the bottle or jar.

25 The object of the improvements is to provide a closure of this class, in which the strength of the capsule is increased by providing a comparatively small thumb-piece in said capsule, and which capsule can, notwithstanding, easily be torn by providing additional slits or weakened portions therein, which additional slits are so located as to be met by the rents produced by pulling the thumbpiece and to again direct said rents 30 away from each other and near the circumference of the capsule.

In the example illustrated in the drawing, I have shown a capsule provided with a 40 downwardly extending flange adapted to be bent or crimped into a groove formed on the upper part of a bottle or jar. But I wish it to be understood, that my invention is not limited to the particular form of the capsule, or to the use of said capsule in combination 45 with the bottle illustrated.

In the drawing, Figure 1, is a cross-section of a capsule showing the same in the form before applying it to a bottle, the tongue however being shown in a slightly 50 raised position. Fig. 2, is a top view of Fig. 1 illustrating the tongue portion and the additional slits or weakened parts, whereby the rent is directed back to the outer parts of the capsule, and Fig. 3, is a cross-section of a 55 bottle provided with the improved closure.

Like letters of reference are used to indicate corresponding parts in all the views.

In the example illustrated, a bottle *a* is formed near its mouth with a cap holder groove *b*. A capsule *c* is provided with a 60 depending flange *d* adapted to be smoothly bent or crimped into or under the cap holder groove *b*. Within said capsule, and on the top of the neck of the bottle, a cork or sealing disk *e* and a sheet metal cork holder disk *i* are 65 located, which, by the pressure exerted by the capsule are held in sealing contact with the face of the bottle.

Referring now particularly to Fig. 2, it will be seen that the capsule *c* is provided, at 70 its flat portion, with a slit *f*, whereby a thumb-piece *g* is formed which can easily be bent upwards by the finger-nail, as shown in dotted lines in Fig. 3, and thereupon grasped by the fingers of the operator to tear the cap- 75 sule. When thus pulling the tongue *g*, the cap would tear substantially after the dotted lines shown in Fig. 2, so that the rents would meet at a point away from the circumference. It would therefore be impossible to 80 remove the cap. To avoid this, I provide further slits or scored portions *h* extending from a part of the line of the rent towards the rim of the capsule and diverging from the direction of the pull exerted on the 85 tongue *g*. The rent will therefore follow the line of the slits or scored portions *h* to the outer ends thereof, wherefrom a new rent will be formed in an unweakened part of the capsule, which rent will strike a second set 90 of slits or scored lines *h*, and so on, until the last rents meet the outer margin of the capsule.

It will readily be understood, that the strength and holding power of my improved 95 closure is not materially impaired by the slits, because bridging portions of unweakened metal extend from one side of the circumference to the other, whereby a very safe and secure closure is produced, which is 100 capable of withstanding the highest internal pressure ordinarily employed in bottled goods. And yet the closure can easily be removed, the rents being always directed 105 outwards by the slits *h*.

I claim:

1. A closure for bottles, jars, or other receptacles, comprising a capsule made of a metal which can easily be torn and adapted to be secured to the mouth of said receptacle 110

and formed with a slit providing a thumb-piece, and with weakened portions located at a distance from the ends of said slit and extending from the lines of rent produced when pulling said thumb-piece and diverging therefrom towards the rim of the capsule.

2. A closure for bottles, jars, or other receptacles, comprising a capsule made of a metal which can easily be torn and adapted to be secured to the mouth of said receptacle and formed with a slit providing a thumb-piece, and with a plurality of successively arranged weakened portions located at a distance from the ends of said slit and at a distance from one another and extending from the lines of rent produced when pulling said thumb-piece and diverging therefrom towards the rim of the capsule.

3. A closure for bottles, jars, or other receptacles, comprising a capsule made of a metal which can easily be torn and adapted to be secured to the mouth of said receptacle and formed with a slit providing a thumb-piece, and with further slits located at a distance from the ends of said first named slit and extending from the lines of rent produced when pulling said thumb-piece and diverging therefrom towards the rim of the capsule.

In testimony whereof I have hereunto set my hand in presence of two subscribing witnesses.

ELISE GOLTSTEIN.
